UNITED STATES PATENT OFFICE.

RUFUS E. ROSE, OF KISSIMEE, FLORIDA, ASSIGNOR OF THREE-FOURTHS TO
HAMILTON DISSTON, JAMES M. KREAMER, AND SAMUEL H. GREY, ALL
OF PHILADELPHIA, PENNSYLVANIA.

DREDGE.

SPECIFICATION forming part of Letters Patent No. 295,202, dated March 18, 1884.

Application filed October 5, 1883. (No model.)

To all whom it may concern:

Be it known that I, RUFUS E. ROSE, of Kissimmee, in the county of Orange and State of Florida, have invented certain new and 5 useful Improvements in Dredges; and I do hereby declare the following to be a full, clear, and exact description of the invention, such as will enable others skilled in the art to which it appertains to make and use the same.

10 My invention relates to a machine for dredging water-courses and excavating canals, ditches, and like water conduits or reservoirs.

The object of the invention is to provide 15 means for continuously removing the earth, &c., by suction, and depositing the same at any desired point, an especial object of the improvement being to provide means for cutting loose the earth and reducing the same to proper condition to be readily acted upon by 20 a suction-pipe having its inductive end arranged in the immediate vicinity of the cutting device.

My invention consists in certain novel constructions and combinations of devices, which 25 will be readily understood from the following particular description in connection with the accompanying drawings, in which—

Figure 1 is a side elevation of a dredging and excavating boat constructed according to 30 my invention, with part of the superstructure walls removed. Fig. 2 is a front view of the same. Fig. 3 is a top view, with a part of the roof and superstructure and also the turn-table omitted, in order to show the machinery. 35 Fig. 4 is a detail side elevation of the cutter, partly in section, and the induction end of the suction-pipe, with part of the earth-guide broken away. Fig. 5 is a top view of the parts shown in Fig. 4. Fig. 6 is an enlarged 40 plan view of the winding and capstan-shaft turning mechanism. Fig. 7 is an enlarged view of the main portion of the turn-table and mechanism supported thereby; and Fig. 45 8 is a view in cross-section taken on the line *x x* of Fig. 7.

The letter A indicates the main central hull of the boat, upon the forward portion of the deck of which is mounted a turn-table, B,

pivoted at *b*, and provided with casters or traveling wheels *b'*, which run on an annular 50 track located on the deck. The turn-table preferably projects beyond the bow of the boat, and has mounted upon it a rotary pump, C, of any suitable construction, to which a suction-pipe, D, is connected by a swivel-joint 55 at *d*, and extends forward and overboard, as shown, its front or induction end terminating in a vertically-arranged semicircular earth guide or shell, E, which is secured and braced to the enlarged front end of the pipe in any 60 suitable manner. The discharge-pipe F of the pump extends vertically, and has its axis coincident with that of the turn-table. The upper end of this discharge-pipe has a swiveling connection with the downwardly-turned 65 inner end of a conducting-pipe, G, which extends laterally from the boat in the present instance, and is supported by suspension chains or rods *h h h* depending from a derrick-beam, H, having its upper end supported by 70 a brace-rod, or chain, *h'*, extending from a frame, I, erected on the forward part of the hull A.

The pump C is driven by a steam-engine, K, which is by preference mounted on the turn-table to counterbalance the pump and its attachments, though it may be located in any other convenient place and connected with the pump by any well-known and suitable motive-transmitting devices. The engine may 75 be of any suitable construction, and need not be here particularly described. The letter K' indicates a belt connecting a belt-wheel on the crank of main shaft of the engine with another belt-wheel on the pump-shaft. 85

The engine K is supplied with steam through a steam-pipe, *m*, which leads from the boilers B, located aft of the turn-table, this steam-pipe passing through the hollow or tubular pivot *b* of the turn-table, and having a swivel-joint at *m'* to allow the turn-table to turn freely. By giving a partial rotation to the turn-table in either direction the forward end of the suction-pipe may be caused to sweep 90 through the arc of a circle, as indicated in Fig. 3, so as to reach the débris to be removed 95

by curved cuts, the boat being advanced a proper distance after each sweep of the pipe.

The devices for operating the turn-table are as follows: N is a segmental rack secured to the deck of the boat beneath the turn-table, and meshing with this rack is a gear-wheel, N', fixed upon a shaft, N², which has its bearings in hangers depending from the turn-table and carries upon its front end a bevel-gear wheel, N³, (see Fig. 8,) with which, on opposite sides, mesh two bevel-gear wheels, N⁴ and N⁵, fixed upon independent shafts, n and n', mounted in hangers depending from the turn-table and carrying belt-wheels n² and n³, respectively, which are connected by belts n⁴ and n⁵ with belt-wheels on the main shaft of the engine. These belts n⁴ and n⁵ are normally so loose that motion will not be transmitted through them to the shafts n and n' unless they are alternately sufficiently tightened. Upon the shafts n and n' are pivoted the arms n⁶ and n⁷, which extend upward through openings in the turn-table, and have pivoted near their upper ends the belt-tightening pulleys n⁸ and n⁹, and these arms are connected by rods n¹⁰ and n¹¹ with the opposite ends of an equal-armed lever, N⁶, pivoted on the front part of the turn-table, and having a forwardly-projecting arm, N⁷, the front end of which is loosely connected to a hand-lever, N⁸, which is arranged to swing laterally with respect to the boat. An attendant on duty on the front part of the turn-table may by operating the hand-lever, as will be readily seen, tighten either of the belts n⁴ or n⁵, and the belt which is tightened causes motion to be transmitted to one of the bevel-wheels, N⁴ or N⁵. These bevel-wheels, though turning in the same direction, respectively cause opposite rotation of the wheel N³, its shaft, and wheel N', which meshes with the rack N, so that by the operation of hand-lever N⁸ the turn-table may be turned as desired.

I will now describe the means for cutting loose the earth and reducing it to such condition that it will be readily drawn into the suction-pipe with the water which flows into the same when the pump is in operation.

The earth-guide or vertical shell E is provided at top and bottom with cross-bars E', in which are formed the bearings for a vertical rotary shaft, E², located at or about the center of the shell E, and having fixed upon its projecting upper end a bevel-gear wheel, E³. Intermediately and at its lower projecting end the shaft E is provided with several series of radial arms, e, carrying at their ends cutters or hoes e'. The shell E is also provided with cross-bars e², which lie between the paths of the several radial arms e, and serve in connection with said arms to break up the earth which has been cut away, and also to reduce pieces of wood, roots, &c., which may be mixed with the earth.

65 O indicates a shaft mounted in bearings at the tops of standards o extending from the

suction-pipe. At its forward end this shaft carries a bevel-gear wheel, O', which meshes with the wheel E³, and at its rear end carries a similar bevel-gear wheel, O², which meshes with another bevel-gear, O³, fixed upon a transverse shaft, O⁴, mounted in standards rising from the turn-table, said shaft carrying a belt-wheel, O⁵, which is connected by a belt, O⁶, with a pulley on the main shaft of the engine. It will now be observed that whenever the pump is in operation a rotary motion will be also transmitted to the cutter-shaft E² and the cutters which it carries, so that as the forward end of the suction-pipe is caused to swing back and forth in the arc of a circle the cutters will cut loose and reduce the earth with which they are brought in contact, so that it will be readily drawn into the suction-pipe by the current of water flowing therein. This is a very important feature of my invention, as by it I am enabled to automatically work all kinds of earth to a condition to be operated upon by the suction-pipe, whereas in operating machines of this class heretofore it has been necessary to cut down stiff clay and other tough earths by hand-spading, or similar means independent of the machines, before the suction-pipe could be efficiently utilized. The cutters do not interfere in the least with the operation of the suction-pipe upon sand, gravel, and loose silt, which does not need to be cut.

The pump may be primed in the usual manner by a steam jet or siphon, (not necessary to be shown in the drawings,) and I provide the suction-pipe in its enlarged front end with an inwardly-opening flap check-valve, f, (see Fig. 4,) to hold the pump charged when stopped temporarily after being first started on commencing work. I also arrange a cut-off gate at f' in the discharge-pipe, so that the pump may be inspected or cleaned out while retaining a charge in the discharge-pipe, said gate being worked by a lever, f². The forward end of the suction-pipe is suspended by a chain, P, having one end connected to a derrick, P', extending forward from the turn-table, said chain passing under a pulley, p, mounted on the suction-pipe, and then up over a guide-pulley, p', on the derrick, and thence over a swiveling pulley, p², at the top of frame I to a drum, Q, mounted upon a transverse shaft, Q', mounted in suitable bearings upon the deck of the boat aft of the turn-table. The drum Q is loose upon its shaft and may be locked thereto, when desired, by a clutch, Q², of ordinary construction. At one end of the drum is a ratchet-wheel, q², with which engages a pawl, q³, to prevent backward turning of the drum when not clutched to the shaft. This shaft extends entirely across the deck and carries at its opposite ends pulleys q, q, for a purpose which will be presently explained. Fixed intermediately upon said shaft is a gear-wheel, Q², which meshes with a smaller gear-wheel, R, mounted

loosely upon a shaft, R', which has fixed upon it a belt-wheel, R², which is connected by a belt, r, with a belt-wheel upon the main shaft of a separate small steam-engine, S, located in 5 the hull of the boat.

The letter r² indicates a sliding clutch of ordinary construction and operation arranged upon the shaft R', to engage the gear-wheel R when desired and lock the same to its shaft. 10 The clutch-operating lever r³ is connected to it in the usual manner, and the said lever is firmly attached to a tumbling-shaft, T, which, extends forward under the turn-table and has its forward end connected to a hand-lever, T', 15 by which it may be turned. By operating the said lever the clutch r² may be caused to lock the wheel R to its shaft, and it will then transmit motion to the drum Q through wheel Q² and its shaft, and the chain P will thus be 20 wound up for raising the forward end of the suction-pipe and its connected devices when it is necessary to repair or inspect the same, the drum of course being first clutched to its shaft from which it must be afterward released to permit said shaft to be used for another purpose, which will be presently explained. 25

The pulleys q q, heretofore referred to, on the opposite ends of shaft Q', I call the "capstan-pulleys," because of their function of feeding the boat forward in connection with ropes having their opposite ends secured on shore or to any suitable permanent supports before and behind the boat. These ropes are 30 designated by U U. They are passed once (or twice if necessary) around the capstan-pulleys q q, and extend thence fore and aft over suitable pulleys and beyond the bow and stern of the boat to anchors or other fixed supports, to 35 which, after they are hauled taut, their ends are made fast. It will now be apparent that when the capstan-pulleys are turned the boat will be propelled accordingly. After each 40 sweep of the suction-pipe and cutter the operator on the turn-table, by moving the hand-lever T', as before described, can clutch the wheel R to its shaft so that it will turn wheel Q², its shaft, and the capstan-pulleys to advance the boat any desired distance, which, in 45 practice, will be from ten to fifteen inches after each full sweep of the suction-pipe and cutter. 50

On each side of the boat are secured the pontoons or scows V V, which, in all kinds of work, 55 serve to buoy and steady the central hull, and, in excavating canals, act as guides to move along the edges of the side banks and hold the boat on a straight course, so that the cutter end of the suction-pipe will be presented to 60 the bank in front in proper position to make uniform cuts.

The conducting-pipe G may be of any desired length, and may be extended from the boat in any direction so as to deposit the 65 excavated earth where there will be no danger

of its sliding back into the canal or other channel.

Having now fully described my invention and explained the operation thereof, I wish it to be understood that I do not limit myself to the precise construction and arrangement of parts as shown in my drawings, but may vary the same in any manner, for the better carrying out of my invention, without departing from the essential principles thereof. For instance, instead of causing the cutter to turn on a vertical axis, it may be arranged horizontally, and motion may be communicated to it from a separate engine from that which drives the pump. Further, instead of transmitting motion by belts to the gearing for turning the turn-table, I may use shafting and gear-wheels, though I prefer the belts, for the reason that should the cutter encounter any obstruction—such as large stones or stumps—the belts will 75 80 85 break before any breakage of the cutter or other parts of the mechanism can occur.

What I claim is—

1. The combination, with a suction-pipe and a vertical shell or earth guide secured thereto, one side or face of said shell being open, of a vertical shaft journaled in said shell, and horizontal knives or cutters secured to the shaft, substantially as set forth. 90

2. The combination, with a suction-pipe and a vertical semi-cylindrical shell secured thereto, of a vertical shaft journaled to the shell, horizontal cutters secured to the shaft, and devices for imparting a rotary motion to the shaft. 95

3. The combination, with a semi-cylindrical earth guide or shell, and a suction-pipe connected to the lower end thereof, of revolving knives and the bars e², rigidly secured to the shield between the knives, substantially as set 105 forth. 100

4. In a hydraulic dredging-machine, the combination of a pump, a suction-pipe swiveled to the pump, and devices for elevating and moving the outer end of the suction-pipe 110 laterally, substantially as set forth.

5. The combination of a turn-table, a pump mounted thereon, a suction-pipe swiveled to the pump, a discharge-pipe connected to the pump, and a valve located in the discharge-pipe, substantially as set forth. 115

6. The combination, with the boat and its turn-table, of the capstan-pulleys, means for turning the same, and means for controlling said capstan-pulleys from the turn-table in 120 any position, substantially as described.

7. The combination of a turn-table, a pump mounted thereon, a derrick, P', a suction-pipe swiveled to the pump, and chains or ropes connecting the induction end of the suction-pipe 125 with the derrick, substantially as set forth.

8. The combination of a turn-table, a pump mounted thereon, a suction-pipe swiveled to the pump and adapted to be moved laterally by turning the table, a steam-engine mounted 130

on the table, a steam-generator independent of the turn-table, and a steam-pipe connecting the generator and engine, the said steam-pipe having a swiveled joint, substantially as 5 and for the purpose set forth.

9. In a dredging or excavating machine, the combination, with a central hull supporting the machinery, of the pontoons or scows secured to the sides of said central hull, sub-

stantially as described, and for the purpose set forth.

In testimony whereof I have signed this specification in the presence of two subscribing witnesses.

RUFUS E. ROSE.
